MATERIAL UNROLLING ATTACHMENT FOR
NAP-RAISING MACHINES

Saul O. Sidore, Manchester, N. H.

Application February 13, 1951, Serial No. 210,685

15 Claims. (Cl. 26—29)

1

The present invention relates to material unrolling attachment for nap-raising machines and has for an object to provide a device constructed and arranged for incorporation in a nap-raising machine for knit goods or other nap-containing fabrics which will act to stretch and smooth the material preparatory to the delivery of the material to the feed rolls and to the nap-raising brush.

In nap-raising machines, as presently constructed and used, two attendants are required, one to each side of the machine constantly engaged in unrolling the knitted material as it is being fed into the machine. Sweaters and other knit goods are ordinarily originally fabricated in several body and sleeve lengths knit in one continuous piece to form a stripe. The stripe has natural rolled longitudinal edges. In order to effect complete raising of the nap it is essential that these longitudinal rolls be removed from the material and that such material be smoothed out transversely prior to being presented to the wire brush roller of the napping machine.

It is an object of the present invention to perform this service automatically by the improved attachment with the elimination of one of the attendants or operators with consequent economy in production.

It is a further object of the invention to provide an unrolling or stretching device for knit goods or fabrics generally, whether incorporated in a nap-raising machine or used individually and independently and which comprises generally a mechanical couple involving a transversely-moving stretching member with a pressure plate or some pressure-imposing means complementary to the stretcher for urging the fabric moved between these parts into such active relationship to the moving stretcher that such stretcher may be effective to stretch, smooth and eliminate the roll.

A still further object of the invention is to achieve the foregoing results in a simple form of mechanical device in which the stretching member or members may be adjusted toward and from one another cross-wise of the path of the fabric to accommodate varying width of stripes.

A still further object of the invention is to provide a device for accomplishing the purposes above stated in which drive means for the feed rollers and drive means for the movable belts or stretchers are so coordinated and integrated that the stretching operation will proceed in proper accompaniment to the longitudinal progress of the stripe to the said rollers and to the napping brush roller.

5 A still further object of the invention is to provide an improved device constructed and arranged to achieve the foregoing objects and purposes in which the stretchers or belts are supported upon transversely-movable and adjustable carriages with appropriate drive means for mutually moving 'said carriages together and apart, in combination with drive means for the belts or other stretchers which will admit of the adjusting movement of the carriages without interfering with the continuous drive for such belts or stretchers.

10 With the foregoing and other objects in view, the invention will be more fully described hereinafter, and will be more particularly pointed out in the claims appended hereto.

15 In the drawings, wherein like symbols refer to like or corresponding parts throughout the several views,

20 Figure 1 is a fragmentary perspective view, with parts broken away and parts shown in section, of a form of material unrolling attachment for nap-raising machines as constructed in accordance with the present invention with one set of the pressure plates raised and with a stripe engaged with the other pressure plate and stretcher belt and also with the feed rollers.

25 Figure 2 is a side elevational view taken from the left side of the machine as illustrated in Figure 1.

30 Figure 3 is a front elevational view, with parts broken away, of the nap-raising machine with the attachment in place.

35 Figure 4 is a vertical transverse fragmentary sectional view taken on an enlarged scale on the line 4—4 in Figure 3.

40 Figure 5 is a vertical transverse sectional view taken on the line 5—5 in Figure 3 and shown on an enlarged scale.

45 Figure 6 is a longitudinal vertical sectional view taken on the line 6—6 in Figure 5.

50 Figure 7 is an enlarged vertical sectional view of the detail of the mechanical couple comprising a stretcher belt and a pressure plate with adjoining parts and with a portion of the stretcher belt broken away, and

55 Figure 8 is a vertical transverse sectional view taken on the line 8—8 in Figure 7.

Referring more particularly to the drawings, 50 10 and 11 designate generally the side frames of a standard form of nap-raising machine in which the stripe 12 is fed from a bin 13 into the nip between feed rollers 14 and 15 on its way to the wire raising brush roller 16.

55 In accordance with the invention a pair of combined stretchers and pressure plates are

mounted in the machine frame in front of the feed rollers 14 and 15. In the single embodiment of the invention illustrated the stretchers are shown in the form of endless belts 17 and 17^a which have their upper runs in substantially horizontal alignment with the nip between the said rollers 14 and 15 so as to receive thereon the underside of the strips 12 as the same moves to the feed rollers 14 and 15. These belts are arranged to move in relatively opposite directions transversely of the machine. The upper horizontal runs of the stretcher belt 17 and 17^a are trained to run over horizontally spaced rollers 18, 18^a and 19, 19^a. The lower runs of such stretcher belt 17 and 17^a are preferably looped downwardly and engaged with drive rollers 20 and 20^a. The journals of the rollers 18, 18^a and 19, 19^a, 20, 20^a are all mounted in bearings in carriages 21 and 21^a which carriages 21 and 21^a have transverse movement, being movably supported for instance on a lateral beam 22 extending cross-wise between the side frames 10 and 11. As shown in Figure 5 this beam 22 may be of dove-tailed cross-section in which event the carriage plates 21 and 21^a may be slipped over the end of the beam 22 before such beam is affixed in the side frames 10 and 11.

As shown more particularly in Figure 3, the journals for the rollers 19 and 19^a are mounted through horizontally elongated slots 23 and 23^a in the carriages 21 and 21^a in order to impose suitable tension on the belts 17 and 17^a to prevent slippage of the drive rollers 20 and 20^a through such belts. Appropriate adjusting devices 24 may be provided in connection with the movable blocks 25 for carrying the adjustable trunnions of the rollers 19, 19^a.

The carriages 21 and 21^a may be moved together or apart by suitable mechanism. In the instance shown worm blocks 26 and 26^a are affixed to the carriages 21 and 21^a by bolts 27 or other appropriate fastening, such worm blocks being oppositely threaded and engaged with a screw or worm shaft 28 having oppositely or right and left hand threaded sections 29 and 29^a for engaging through said worm blocks 26 and 26^a whereby rotation of the worm shaft 28 in one direction will cause the blocks and carriages to be moved together toward or away from the center of the machine to bring the belts 17 and 17^a closer together for narrower stripes or farther apart for wider stripes.

The worm shaft 28 may be driven from any appropriate source. In this instance by the chain and sprocket drive 30 from an electric or other motor 31 as shown in Figure 3. This motor 31 is preferably a reversible motor and provided with the conventional pilot circuit controlled by pairs of limit switches 32 and 33 for each carriage. These limit switches are shown in Figure 1 as being slidably mounted on a conductor bar 34 with set screw adjustment 35, 36. Tables 37 and 37^a affixed to and moving with the carriages 21 and 21^a are provided with downwardly extending projections 38 and 39 at opposite end portions thereof positioned to engage and actuate the limit switches 32 and 33 respectively on the outer and inner movements of the carriages. The tables 37 and 37^a will extend in substantially horizontal alignment with the belts 17 and 17^a and such tables receive the fabric or stripe 12 on its way to the belts and feed rollers 14 and 15 and such tables tend to support and protect the stripe from entanglement with the mechanism of the carriages.

The belts 17 and 17^a are driven by appropriate mechanism. In the instance shown, a shaft 40 is journaled transversely of the machine and carries thereon a pair of bevel pinions 41 and 41^a disposed in mesh with relatively opposite sides of bevel pinions 42 and 42^a which are fixedly mounted on the trunnions of the drive rollers 20 and 20^a. See Figures 5 and 6.

The bevel pinions 41 and 41^a are slidable along their drive shaft 40 along keys or splines 43 which compel the bevel pinions 41 and 41^a to rotate with the shaft 40 at all times. The bevel pinions 41 and 41^a are carried in gear boxes 44 and 44^a supported and movable with the carriages 21 and 21^a respectively.

The shaft 40 may be driven in any appropriate manner as for instance by a chain drive 45 shown in Figure 2 which may come from any suitable power take-off on the machine. As shown in Figure 3 a main motor 46 through belt and pulley drive 47 drives the brush shaft 48. As shown in Figures 2 and 3 through the sprocket and chain drives 49, 50, 51 the chain drive 45 drives the shaft 40. In conjunction with each belt 17, 17^a there are preferably mounted a pair of individual movable pressure plates 52, 52^a and 53, 53^a.

As shown more particularly in Figures 1, 7 and 8, the pressure plates have upstanding flanges 54 provided with vertical elongated slots 55 for enabling the pressure plates to be vertically adjusted with respect to their carrying studs 56 which are threaded into rocking frames 57 pivoting about the pivot bolts 58. The frames 54 have vertically extending ribs 59 slidable vertically in grooves 60 in the adjacent faces of the rocking frames 57. The ribs 59 and grooves 60 form complementary guides for guiding the up and down adjusting movements of the pressure plates. The pressure plates by gravity tend to drop downwardly upon the belts and are restrained by the lower ends of set screws 61 engaging the respective studs 56. The set screws are threaded through the upper edges of the flanges 54. By rotating the set screws 61 the same may be moved up or down so as to change the position of the stop effect. In this way the gap between the pressure plates and endless belts is adjusted and governed to meet the requirements of fabrics of varying thickness.

The rocking frames 57 have outwardly extending arms 62 engaged by one or more springs 63 which are connected at their lower ends, Figure 7, to adjusting devices which may comprise threaded eye rods 64 having lock nuts 65 and 66 above and below respectively a collar 67 through which the threaded rod 64 is vertically adjustable with the nuts 65 and 66 controlling the degree of adjustability. When the threaded rods 64 are adjusted upwardly the entire weight of the pressure plates may be imposed upon the fabric. By adjusting the rods 64 downwardly the springs 63 may be placed under increased tension to thus take up some of the weight of the pressure plates and correspondingly remove such weight from the stripe.

In the use of the device, the stripe 12 will be initially drawn up on the tables 37 and 37^a and over the belts 17 and 17^a, it being understood that the pressure plates 52 and 53 will be raised as indicated at the left in Figure 1. These pressure plates may be raised by hand and after the hand is removed the pressure plates will automatically drop in place and urge the edge portions of the stripe against the stretching belts 17 and 17^a.

The leading edge of the stripe is fed into the nip of the feed rollers 14 and 15 and the material is then napped in the conventional manner. The feed rollers 14 and 15 pull the material longitudinally into the napping machine over the tables and between the belts and pressure plates.

Before starting the operation the carriages are adjusted by energizing the motor 31 so that the belts 17 and 17^a may be moved to correct position towards or away from one another to accommodate the width of the stripe about to be fed. When this adjustment has been effected the limit switches 32 and 33 de-energize the motor 31 either at the narrowest or widest limits permissible by the width of machine.

The main motor 46 is then energized to drive the belts and feed rollers as well as the napping brush and the stripe will thereupon move longitudinally into the machine and at the same time be subjected to transverse stretching movements of the belts 17 and 17^a which cooperating with their pressure plates will unroll the side edge portions of the stripe and stretch and smooth the stripe so as to place it in most favorable condition for the subsequent napping operation; namely, presenting the transverse width of the stripe to the napping brush in order to obviate the skipping or the omission of napping of certain blind spots transversely of the material. The present invention affords with the above described construction a device for assuring of one hundred per cent of the napping of the transverse dimension of the stripe fed into the machine.

The rock frames 57 pivotally carrying the pressure plates may be limited in the downward movements of the pressure plates by complementary stops 70, 71. The springs 63 are in effect an adjustable counter balance for the weight of the plates carried by the rock frames 57. The plates impose their weights upon the material both by a vertical sliding movement in the rock frames 57 and also by the angular movement of the rock frames 57 about the pivots 58.

Although I have disclosed herein the best form of the invention known to me at this time, I reserve the right to all such modifications and changes as may come within the scope of the following claims.

What I claim is:

1. In a material unrolling attachment for nap-raising machines, the combination with the usual feed rollers, of a pair of endless belts arranged in front of the feed rollers to move transversely of the path of the material in relatively opposite directions and positioned to engage beneath the material, and pressure plates positioned to engage the upper surface of the material above said belts.

2. In a material unrolling attachment for nap-raising machines, the combination with the usual feed rollers, of a pair of endless belts positioned to engage the material at its underside forwardly of the feed rollers and disposed to move in relatively opposite directions transversely of the path of the material in moving to the feed rollers, and means disposed above said belts for exerting pressure downwardly upon the material to urge such material against the belts.

3. In a material unrolling device, endless belts positioned to engage one side of the material and to move in relatively opposite directions, pressure plates positioned to engage the opposite side of the material substantially opposite said

belts, and means for feeding said material between said pressure plates and endless belts.

4. In a material unrolling device, oppositely moving means adapted to engage one side of the material, and pressure means arranged substantially opposite said first-named means and engaging the opposite side of the material to urge the material against said first named means.

5. In a material unrolling device, stretching members movable in relatively opposite directions, pressure members substantially opposite said stretching members, and feed means for drawing the material between said stretching and pressure members in a direction angularly to the direction of movement of said stretching members.

6. In a material unrolling device, stretching members movable in relatively opposite directions, pressure members substantially opposite said stretching members, feed means for drawing the material between said stretching and pressure members in a direction angularly to the direction of movement of said stretching members, and drive means for driving both said stretching members and feed means.

7. In a material unrolling device, stretching members movable in relatively opposite directions, pressure members substantially opposite said stretching members, feed means for drawing the material between said stretching and pressure members in a direction angularly to the direction of movement of said stretching members, drive means for said stretching members, drive means for said feed means, and integrating means coupling both said drive means in a predetermined relation for unrolling the material at a rate proportional to the feed movement of the material.

8. In a material unrolling device, stretching members moving in relatively opposite directions for contacting one side of the material, pressure means engageable with the opposite side of the material positioned to urge the material against said stretching members, a carriage for movably supporting each stretching member and its complementary pressure means, and means for movably supporting said carriages for movement toward and from one another.

9. In a material unrolling device, a frame, carriages movably mounted on said frame, means for moving said carriages together or apart, movable stretchers carried to move relatively to said carriages, a drive shaft mounted in said device, and gearing between said shaft and stretchers carried to move with said carriages and coupled to drive said stretchers, said gearing slidably relatively along said shaft and having drive gears fixed to rotate with said shaft.

10. In a material unrolling device, an endless belt positioned to receive the material, drive means to move said belt, a pressure plate above the belt and means for suspending the plate for vertical sliding movement to enable its weight to be imposed at least partially upon the material engaged with said belt.

11. In a material unrolling device, an endless belt adapted to receive the material, drive means to move the belt, a pressure plate mounted for vertically adjustable movement above said belt, and means to adjust the lower limit of movement of said plate.

12. In a material unrolling device, an endless belt, drive means to drive said belt, a pressure plate above the belt, and a rock frame for supporting said plate.

13. In a material unrolling device, an endless belt; a pressure plate above said belt adapted to rest by gravity upon the material on the belt, and means to adjust the effective weight of the pressure plate upon the material.

14. In a material unrolling device, an endless belt, drive means to drive the belt, a rock frame, a pressure plate above the belt vertically slidable in said rock frame, adjusting means to determine the lower limit of descent of the plate in said frame, means to secure the plate in adjusted position, and means for placing said rock frame under adjustable tension in counter-balance of said plate.

15. In a material unrolling device, relatively movable carriages, movable belts thereon, drive means for moving said belts in relatively opposite

directions, means for moving said carriages toward and from one another, rock frames on said carriages, pairs of pressure plates above each belt vertically adjustable in their respective rock frames, and adjustable counter-balance means for the plates connected to said rock frames and supported by the respective carriages.

SAUL O. SIDORE.
